(57) **CLAIM**

The ornamental design for a wearable device, as shown and described.

DESCRIPTION

FIG. 1 is a top perspective view of a wearable device;
FIG. 2 is a front side view of the wearable device;
FIG. 3 is a rear view of the wearable device;
FIG. 4 is a top view of the wearable device;
FIG. 5 is a bottom view of the wearable device;
FIG. 6 is a left side view of the wearable device; and,
FIG. 7 is a right side view of the wearable device.

The broken lines shown in the figures illustrate portions of the display device that form no part of the claimed design. The oblique shade lines in the figures show a transparent, reflective, or shiny surface, and not surface ornamentation.
